(57) **CLAIM**

The ornamental design for a steam iron, as shown and described.

DESCRIPTION

FIG. 1 is a perspective view as seen from the top, front and left side of a steam iron showing my new design;

FIG. 2 is a left side elevational view thereof;

FIG. 3 is a right side elevational view thereof;

FIG. 5 is a front elevational view thereof;

FIG. 6 is a rear elevational view thereof;

FIG. 4 is a top plan view thereof; and,

FIG. 7 is a bottom plan view thereof.

The broken lines in FIG. 1 showing a cord guard and the broken lines showing soleplate vents in FIG. 7 are for illustration only and form no part of the claimed design.
